UNITED STATES PATENT OFFICE.

MIKE LYNCH, OF STURGIS, MICHIGAN.

CRUDE-OIL BURNER.

SPECIFICATION forming part of Letters Patent No. 517,411, dated March 27, 1894.

Application filed May 29, 1891. Serial No. 394,591. (No model.)

To all whom it may concern:

Be it known that I, MIKE LYNCH, a citizen of the United States, residing at Sturgis, in the county of St. Joseph and State of Michigan, 5 have invented new and useful Improvements in Crude-Oil Burners, of which the following is a specification, reference being had therein to the accompanying drawings.

This invention relates to new and useful 10 improvements in crude oil burners, and the improvement consists in the peculiar construction and arrangement of pipes and openings therein, in connection with deflectors; and the object of my invention is to inject 15 into a furnace and disseminate therein crude oil or other liquid fuel, in a way to effect complete combustion with a minimum of noise and effluvia as hereinafter more fully described.

20 In the drawings which accompany this specification Figure 1 is a perspective view of my burner. Fig. 2 is a longitudinal sectional view thereof.

My burner is primarily formed of two metal 25 pipes.

"A" represents the exterior pipe and has at its rear end a screw thread fitting in a T coupler "B," connecting it with a steam pipe "C," and a steam tight packing box "D," both 30 secured to the T coupler "B" by screw threads, as shown in Fig. 2. The other end of "A" is enlarged in a spherical form, which is placed inside the firebox when in operation, to effect a drying of the steam contained 35 therein, before issuing from the pipe, it being believed that dry steam is effective in lessening the noise in combustion of the oil. The pipe "A" extends beyond the enlargement just referred to, at its normal diameter a suitable length, and is finished in the inside, at the end, with an annular shoulder "a."

"E" represents the inner pipe which passes through the steam tight packing box "D" and the T coupler "B" into the pipe "A," and 45 extends its entire length, forming therewith a steam chamber "p," and has at its forward end a circular metal cap "F" screwed thereon, which forms with the shoulder "a" in the forward end of the pipe "A," a valve seat for 50 the outlet of the steam. A rectangular opening "b" is cut in the end of the cap, through

which the oil emerges, and the cap is furnished on its periphery with rectangular flanges "c" as guides, preferably four in number, to slide against the inside of "A," and keep the pipe 55 "E" in a central position therein. The rear end of the pipe "E" is attached to the feed pipe "G" connected with a tank of oil or other suitable supply, and is moved horizontally inside of pipe "A" by means of a collar 60 "d" revolving on a screw thread cut on the exterior of "E," and receiving the jaw of a pawl "e" attached to the steam pipe "C," and is actuated by the lever "f."

Encircling the end of the pipe "A," is the 65 metal plate "H," secured thereto and fitted with two flanges "g" "g'," projecting in front and supporting the metal deflectors "I I" on hangers "h h," which are pivoted on the lower flange "g," and projected through the upper 70 flange "g'" and then bent outward, and connected by the arms "i i" and the pin "j" to a rod "J" which passes through a slot "k" in the plate "H," and also through a standard "l," secured to the pipe "A," and is screw 75 threaded near the end, on which a wheel "m" a barrel "n" rigidly connected together, and interiorly screwthreaded and revolve, and open and close the deflectors to any desired position. A rectangular metal bar "O" 80 is placed vertically across the inside of the end of the pipe "A" close to the inner edges of the deflectors "I" "I," and where it crosses the opening "b" in the cap "F," it is formed to a wedge shape, and prevents the oil from 85 being projected forward between the deflectors.

The operation of the machine may be described as follows: The oil is admitted and regulated by a stop-cock, or other suitable 90 device, through the feed pipe "G" into the interior pipe "E," and the steam may be let on at the same time and by the same method, from the steam pipe "C" into the outer pipe "A" from which it escapes into the furnace between the guides "c" on the cap "F" intermingling and carrying with it the oil emerging from the opening "b" in the cap "F," after leaving the pipes, the mingled jet of steam and oil strikes the deflectors, placed at 95 any desired angle, and is immediately spread out under and up the sides of the boiler in a 100

thin sheet of spray and is consumed at once without smoke or effluvia. The combination is perfect and the noise vastly reduced. The volume of steam at the outlet is controlled 5 by the valve formed of the cap "F" on the end of the pipe "E" and the annular shoulder "a" in the interior of the pipe "A" as hereinbefore shown.

Having thus described my invention, what 10 I claim as new, and desire to secure by Letters Patent, is—

1. In a crude oil burner the combination with the interior pipe "E" having the cap "F" screwed thereon fitted with guides "c" 15 and an opening "b" cut in the end of the same for the emission of oil; of the exterior pipe "A" with the interior ring or annular shoulder "a" at the forward end and having

the bar "o" placed therein, substantially as and for the purpose set forth. 20

2. In a crude oil burner the combination with the exterior pipe "A" provided with the annular interior shoulder "a," and the bar "o" placed therein, of the plate "H" with the flanges "g" "g'" supporting the deflectors "I" "I" on hangers "h" "h" pivoted on lower flange "g" and projecting through upper flange "g'" and then bent outward and connected to rod "J" by bars "h" "h" and pin "j" substantially as and for the purpose 25 set forth. 30

MIKE LYNCH.
